TRANSPARENT PROTECTIVE SHIELD
FOR HAIR SPRAYINGAline L. Ross, 12080 SW. 116th Ave.,
Tigard, Oreg. 97223

Filed Jan. 31, 1967, Ser. No. 5,637

Term of patent 14 years

(Cl. D86—10)

FIG. 1 is a front view of the transparent protective shield embodying my new design, the broken lines indicating the position in which it is used;

FIG. 2 is a side elevation of the protective shield; and
FIG. 3 is a rear view of the same.

I claim:

The ornamental design for a transparent protective shield for hair spraying, substantially as shown and described.
